(57) **CLAIM**

The ornamental design for a desk caddy, as shown and described.

DESCRIPTION

FIG. 1 is an upper perspective view of the desk caddy showing my design in the assembled configuration.

FIG. 2 is a side elevation view thereof;

FIG. 3 is an opposite side view thereof;

FIG. 4 is a front elevation view thereof;

FIG. 5 is a back elevation view thereof;

FIG. 6 is a top plan view thereof;

FIG. 7 is a bottom plan view thereof;

FIG. 8 is still another perspective view, showing the unfolded configuration; and,

FIG. 9 is yet another perspective view, showing the folded configuration.

The broken line features are shown for the purpose of including features on the desk caddy that form no part of the claimed design.
